195,994

GAUGE UNIT FOR MEASURING AND REGULATING GASES UNDER HIGH PRESSURE OR SIMILAR ARTICLE

William Sandler, 63-33 98th Ave., Forest Hills, N.Y.

Filed July 27, 1959, Ser. No. 56,940

Term of patent 14 years

(Cl. D52—6)

FIG. 2

FIG. 1

FIG. 4

FIG. 3

FIG. 5

FIG. 1 is a front elevational view of a gauge unit for measuring and regulating gases under high pressure or similar article, showing my new design;

FIG. 2 is a top view thereof;

FIG. 3 is a side elevational view of the gauge unit shown in FIG. 1;

FIG. 4 is a left-hand side elevational view of the gauge unit;

FIG. 5 is a bottom plan view of the gauge unit.

The rear of the gauge unit is substantially plain.

The dominant features of my new design reside in the portions shown in full lines in the drawings.

I claim:

The ornamental design for a gauge unit for measuring and regulating gases under high pressure or similar article, substantially as shown and described.
